UNITED STATES PATENT OFFICE.

TEIJIRO YABUTA, OF SETAGAYA-MACHI, EBARA-GORI, JAPAN, ASSIGNOR TO ZAIDAN HOJIN RIKAGAKU KENKYUJO, OF TOKYO, JAPAN.

PROCESS OF PREPARING MALEIC AND SUCCINIC ACID FROM FURFURAL BY ELECTROLYSIS.

No Drawing. Application filed March 31, 1926, Serial No. 98,917, and in Japan June 22, 1925.

This invention relates to the preparation of maleic and succinic acid from furfural by electrolysis and the object of the invention is to prepare these acids by far better efficiency 5 than any other process hitherto known.

In carrying out my invention, furfural dissolved or suspended in an acid or a salt solution, is oxidized by electrolysis. Maleic and succinic acid may be isolated from the resulting oxidation product which consists of their mixture.

Moreover, by using the proper materials for the electrodes and also by employing the proper current density, either maleic or succinic acid can be obtained as the main product.

Maleic acid can easily be converted into fumaric acid by the usual methods. By the reduction of maleic as well as fumaric acid, 20 succinic acid can also be produced.

Example 1.

A two-compartment cell, the compartments being separated from each other by a porous 25 diaphragm is employed. The anodic compartment contains 5 per cent sulphuric acid in which furfural is dissolved or suspended, whilst the cathodic compartment contains 10 per cent sulphuric acid. The electrodes are 30 advantageously made of lead pipe coils which serve also as cooling means by passing water through them. A relatively low current density, for example, say, 0.02 amps. per sq. cm. is employed and the temperature kept at 35° C. The electrolysis is continued, until the anolyte no longer gives the characteristic reaction of furfural with aniline acetate, and it is then moderately concentrated. On cooling 40 mixed crystals of succinic and maleic acid (80 per cent and 20 per cent respectively) separate. They are collected and isolated from each other by fractional crystallization.

Some more crystals are obtained from the mother liquor on further evaporation, but the liquid is preferably utilized as the anolyte 45 for the next operation.

If succinic acid alone is desired, the current is reversed in the same apparatus after the furfural is perfectly oxidized. The maleic acid mixed with succinic acid, is reduced and 50 converted into succinic acid. The cathodic solution is moderately concentrated and cooled. The crystals of succinic acid which 55 separate are collected and purified by recrystallization from hot water.

Example 2.

The electrolysis is carried out as in the Example 1, except a lead peroxide anode is used instead of a lead one, and a relatively high 60 current density, for example, say, 0.06 amperes per sq. cm. is employed. In this case, chiefly maleic acid is produced and the yield reaches 75 per cent of the theory.

It is advantageous to use the anodic solution obtained in this case for the preparation 65 of fumaric acid. For this purpose, an amount of sodium chloride corresponding to the sulphuric acid contained in the solution, is added and boiled for about half an hour. On 70 cooling, the fumaric acid converted from maleic acid by the catalytic action of hydrochloric acid, crystallizes out. It is collected and recrystallized from hot water.

In these operations described above, increased yield is obtained by the addition of 75 vanadium, cerium or manganese compounds as catalysis in the anolyte.

I claim:

The process of preparing maleic and succinic acids which comprises electrolyzing an acid solution of furfural.

In testimony whereof I affix my signature.

TEIJIRO YABUTA.
